UNITED STATES PATENT OFFICE

FRANK J. SOMERVILLE, OF MONTREAL, QUEBEC, CANADA, ASSIGNOR TO IMPERIAL
TOBACCO COMPANY OF CANADA LIMITED, OF MONTREAL, QUEBEC, CANADA

CIGAR HEAD KNURLING AND PUNCHING DEVICE

Application filed June 10, 1932. Serial No. 616,506.

This invention relates to the manufacture of cigars and comprises a cigar head knurling and punching device for producing cigars of the kind described in my co-pending 5 application, Serial No. 611,993, filed May 18, 1932.

In the application mentioned above I have described an improved form of cigar having one end punched to provide a smoke bore 10 which does away with the necessity of biting or cutting off that end of the cigar which is placed in the mouth. As also described in said application, the portion of the wrapper which is penetrated by the punch is turned 15 or tucked into the outer end of the bore formed in the filler in order to secure this end of the wrapper against unravelling and to prevent contact of the tongue with rugged edges of the wrapper or that portion of the 20 filler that would otherwise be exposed at the outer end of the bore.

The object of the present invention is to provide means whereby the punching of the bore and the turning of the wrapper into the 25 outer end of the bore may be conveniently accomplished in a single operation.

The essential feature of the invention consists in attaching a punch to a cigar head knurling device of substantially conventional 30 form. When the end of the cigar is inserted in the knurling device to "firm up" and finish off the wrapper covering this end of the cigar, the punch pierces the wrapper and penetrates the filler to form a bore of the 35 size and length dependent upon the type of punch used for this purpose. The punch is preferably made of tapering construction so that as it penetrates the filler it causes the portions of the wrapper surrounding the 40 opening initially made therein by the point of the punch to be turned or tucked into the outer end of the bore which is being formed in the filler so that, in the finished cigar, there is no exposure of the filler at the outer 45 end of the bore.

Proceeding now to a more detailed description of the invention, reference will be had to the accompanying drawings, wherein—

50 Figure 1 is a top plan view of a cigar head

knurling and punching apparatus provided in accordance with this invention.

Figure 2 is a side view of said apparatus.

Figure 3 is an end view of said apparatus.

Figure 4 is a view partly in longitudinal 55 section and partly in elevation of the combined knurling and punching head forming part of said apparatus.

Figure 5 is a fragmentary view of a cigar produced in accordance with this invention. 60

Referring more particularly to the drawings, 11 designates a horizontal bearing sleeve formed at the upper end of a standard 12 rising from a suitable base 13, said bearing sleeve containing a bushing 14 held in place by a set screw 15 and a lock nut 16. A shaft 17 is rotatably mounted in the bushing 14 with the ends of the shaft projecting beyond corresponding ends of the bearing sleeve 11. One end of shaft 17 carries a driving pulley 18 keyed or otherwise suitably fixed thereto. The other end of said shaft carries a knurling 65 head of the usual type including a ring 19, a spindle 20, and the usual arrangement of curved knurling arms 21. As herein shown, the spindle 20 is fixed in a bore 22 formed in the last mentioned end of the shaft 17 so as to rotate with said shaft when power is applied to the pulley 18. The punch provided 70 in accordance with this invention is indicated at 23 and has one end fixed in a bore 24 formed in the outer end of the knurling head spindle 20. The pointed end of the punch terminates short of the ring 19 and is centered with respect to the ring and curved knurling arms 75 21.

The end of the bushing remote from the driving pulley is extended beyond the corresponding end of the bearing sleeve 11 to provide a support for a U-shaped member 26. 80 One arm 27 of this member is formed to provide a horizontal cigar support 28 having its upper surface transversely curved as indicated at 29 in Fig. 3. The other arm 30 of said member is formed to provide a split 85 clamp 31 which is held to the extended end 14a of the bushing by means of the fastening screw 33. The inner end of the horizontal support 28 is spaced from the ring 19 of the knurling head and this space is bridged 90 100

during the knurling and punching operation by a displaceable cigar guiding and centering member indicated at 35. As herein shown, said member 35 comprises a tube open at both 5 ends and having one end formed to provide a flange 36 and a pair of supporting arms 37 and 38 of unequal length. These arms 37 and 38 are pivoted as indicated at 39 to the side members of the clamp 31 so as to permit 10 the member 35 to be swung from the horizontal position shown in full lines in Fig. 2 to the vertical position shown in dotted lines. The long arm 38 is provided near its free end with an opening 40 adapted, in the horizontal 15 position of the member 35, to register with a socket 41 formed in the bearing sleeve 11 so that a locking pin 42 may be passed through the arm into said socket to secure the member 35 in its horizontal position.

20 At the end remote from the flange 36 the member 35 has its lower portion cut away to provide a notch 35a receiving the inner end of the horizontal cigar support 28 so that the lower wall of the bore formed in said member 25 is thus aligned with the curved surface 29 of the cigar support.

In the operation of the apparatus described herein, the cigar supporting and centering member 35 is secured in the position shown in 30 Fig. 2 and a driving belt connected to the pulley 18 to impart rotation to the shaft 17 and to the knurling and punching head fixed to said shaft. A cigar 44 is then placed on the support 28 as shown in Fig. 2 with the 35 head or end of the cigar which is to be placed in the mouth inserted within the tubular guide and centering member 35. The cigar is then pushed through the member 35 into engagement with the knurling arms 21 which 40 perform the usual knurling operation on the portion of the wrapper covering this end of the cigar. At the same time the punch 23 penetrates the wrapper and filler and causes portions of the wrapper in contact with the 45 punch to be forced into the outer end of the bore which is thereby formed in the filler.

In Fig. 5 I have shown a portion of a cigar having the mouth end bored in accordance with this invention. In this view 45 designates the bore which is formed in the filler by the punch 23 and 46 designates that portion of the wrapper which is tucked into the outer end of the bore.

From the foregoing it will be apparent that 50 the apparatus described herein provides a simple and efficient medium whereby the punching of the wrapper and the filler to provide a smoke or draft bore and the tucking in of the wrapper at the outer end of the bore 55 are conveniently accomplished in a single operation.

Having thus described my invention, what I claim is:—

1. The combination with a rotary cigar 60 end knurling device of a punch, and means

mounting the punch on the knurling device, said punch being adapted to penetrate the cigar wrapper and filler to form a smoke or draft passage in the filler during the knurling 70 operation.

2. A rotary cigar end knurling device equipped with a punch mounted thereon and adapted to penetrate the cigar wrapper and filler to form a draft passage in the end of the cigar engaged by the knurling device, 75 said punch being tapered toward its pointed end to force the punched portion of the wrapper into the outer end of the draft passage as the punch penetrates the filler.

3. The combination of a rotary cigar end 80 knurling device, a punch mounted on said knurling device and adapted to penetrate the cigar wrapper and filler at the end engaged with said knurling device, a cigar support mounted in front of the knurling device 85 in spaced relation thereto, said support affording a rest for the cigar during the operation of pushing it into engagement with the knurling device and a tubular cigar centering member mounted between the knurling device and the adjacent end of the support 90 in a position to ensure proper centering of the cigar with respect to the knurling device and the punch as it is advanced into engagement therewith.

4. The combination of a rotary cigar end 95 knurling device mounted to rotate about a horizontal axis; a centered punch mounted on the knurling device adapted to penetrate the cigar wrapper and filler at the end engaged with said knurling device, a horizontal cigar support mounted in front of the knurling device at a suitable level to support the cigar during the operation of advancing it 100 into engagement with said knurling device, a tubular cigar centering member normally disposed in a horizontal position between the support and the knurling device to ensure proper centering of the cigar during its advance into engagement with the knurling device and the punch carried by the knurling device, and means mounting said centering member for swinging movement to an inoperative position.

5. A combined cigar end knurling and 115 punching device comprising a spindle, a ring concentric with the spindle but spaced from one end thereof, a series of curved knurling arms connecting the ring to the said end of the spindle, and a punch fixed to the said end of the spindle, said punch being centered with respect to the ring and the curved knurling arms.

6. The combination of a rotatably mounted shaft, a knurling device including a spindle fixed to rotate with said shaft, a series of curved knurling arms carried by said spindle and a ring carried by said arms, a punch fixed to said knurling device to form a smoke bore in the end of a cigar as the latter is 120 125 130

advanced into engagement with the curved arms of the knurling device, a cigar support mounted in front of said knurling device and in spaced relation thereto to support 5 a cigar during its advance into engagement with said knurling device, a tubular guide member normally supported in the space between the knurling device and said cigar support to center the cigar as it is advanced from

the support into engagement with said knurling device and punch, said guide member being carried by a pair of swinging arms permitting the same to be displaced from its position between said knurling device and 70 support.

In witness whereof, I have hereunto set my hand.

FRANK J. SOMERVILLE.
